CONTAINER AND ITS COVER

Robert Ensko, Freeport, N. Y., assignor to Seeman Brothers, Inc., New York, N. Y., a corporation of New York

Application September 28, 1934, Serial No. 745,898

4 Claims. (Cl. 229—5.5)

This invention relates to containers and removable covers therefor.

In recent years an inexpensive container has been developed comprising a cylindrical body portion of relatively heavy paper or cardboard, usually made in tubular form by spiral wrapping about a mandrel. The lower ends of such containers are usually provided with a suitable closure member, preferably of tin plate permanently secured to the lower edge of the paper cylinder. The upper ends of such containers are frequently provided with removable metal covers, and in many cases it is desirable that the covers be readily removable and replaceable.

In the past, much trouble has been experienced, and the potential use of containers of this general type has been greatly restricted, because of the difficulty of securing an accurate fit between the paper cylinder and the metal cover. This difficulty results from the fact that there is considerable variation in the outside diameters of the paper cylinders, caused by variations in the thickness of the paper stock, variations in wrapping, and even variations in atmospheric conditions both during manufacture and subsequently. The metal covers can be made to conform accurately to specified dimensions within reasonably close limits, but if made of a size to fit the larger paper cylinders properly, the covers are so loose on the smaller cylinders that they frequently fall off. On the other hand, if made of a size to fit the smaller cylinders properly, the covers bind so tightly on the larger cylinders that it is sometimes impossible to remove them without destroying the container. In practice it is attempted to select a cover size intermediate the two extremes, but even so some covers bind on the larger cylinders, and some are loose on the smaller cylinders.

The difficulty is magnified in the case of covers which fit too tightly by the fact that it is customary to provide a fairly deep vertical flange or skirt on the cover, in order that the cover may be easily handled by the user. If the cover is tilted slightly as it is attempted to remove it, the skirt binds tightly against the wall of the cylinder, thus increasing the difficulty of removal.

It is an object of the present invention to overcome these difficulties and to provide a cover which will fit securely on cylinders of slightly different outside diameters, and still be readily removable and replaceable.

Other objects and advantages of the invention will appear hereinafter.

A preferred embodiment of the invention selected for purposes of illustration is shown in the accompanying drawing, in which,

Figure 1 is a front elevation showing the container with the cover on, and

Figure 2 is a vertical section on a larger scale through the axis of the container.

Referring to the drawing, the container comprises a cylindrical body portion 1 having its lower end closed in any suitable manner, as by the metal closure member 2 which is permanently secured to the cylinder body portion.

The cover member 3, preferably of metal such as tin plate, is intended to be easily removable and replaceable and comprises a circular disk top portion 4 having a skirt or flange depending from its periphery. The said skirt has a constricted upper portion 5 adjacent the top of the cover, which portion has an inside diameter slightly less than the inside diameter of the lower portion 6 of the skirt. In the preferred embodiment illustrated the two portions are joined by a substantially horizontal off-set portion 7.

The inside diameter of the constricted portion 5 of the skirt should be such as to engage snugly the top of the outside wall of the container, and in view of the variations in the outside diameters of the containers as previously described, the inside diameter of the constricted portion 5 of the skirt should be slightly less than the outside diameter of the smaller containers. In this manner, a frictional engagement is obtained between the outside wall of the container and inside wall of the portion 5 of the cover which is sufficient to retain the cover on even the smaller containers. In the case of the larger containers, the portion 5 of the cover compresses slightly the upper edge of the container, which being a free edge is somewhat yielding.

In the case of the lower portion 6 of the cover, the inside diameter is preferably slightly larger than the outside diameter of the container, so that in the case of the smaller containers, at least, an annular space 8 is left between the inside wall of the portion 6 and the outside wall of the container. In the case of the larger containers, the inside diameter of the portion 6 may be the same or even slightly less than the outside diameter of the container without causing undue difficulty in removing the cover, but it is preferable that the inside diameter of the portion 6 be slightly larger than the outside diameter of the container, so that the cover is retained on the container solely by the frictional engagement between the portion 5 and the container.

Preferably the inside walls of both the upper portion 5 and the lower portion 6 of the skirt are substantially vertical and parallel to the outside wall of the container.

5 It is also preferable that the upper portion 5 should extend downwardly less than half the total depth of the skirt.

While the invention has been described as applied particularly to containers comprising a paper or cardboard cylindrical body portion, it will be understood that it may also be useful in connection with containers made of other materials, particularly where such containers differ slightly in their outside diameters.

10 15 It will be understood that the invention may be variously modified and embodied within the scope of the subjoined claims.

I claim as my invention:

1. A container comprising a cylindrical body portion of compressible material such as cardboard, and a removable metal cover therefor, said cover having a circular disk top portion, and a skirt depending from the periphery of said disk, a portion of said skirt adjacent said top having an inside diameter slightly less than the normal outside diameter of said cylindrical body portion, so as to frictionally engage said body portion and slightly compress the same, and the lower portion of said skirt having an inside diameter slightly 25 larger than the inside diameter of the upper portion of the skirt.

2. A container comprising a cylindrical body portion of compressible material such as cardboard, and a removable metal cover therefor, said cover having a circular disk top portion, and a skirt depending from the periphery of said disk, a portion of said skirt adjacent said top having an inside diameter slightly less than the normal outside diameter of said cylindrical body portion, so 30 35

as to frictionally engage said body portion and slightly compress the same, and the lower portion of said skirt having an inside diameter slightly larger than the inside diameter of the upper portion of the skirt, the inside walls of said skirt being substantially vertical and parallel to the outside wall of the said body portion of the container except for an offset portion joining the two portions of different inside diameters.

5

3. A container comprising a cylindrical body portion of compressible material such as cardboard, and a removable metal cover therefor, said cover having a circular disk top portion, and a skirt depending from the periphery of said disk, a portion of said skirt adjacent said top having an inside diameter slightly less than the normal outside diameter of said cylindrical body portion, so as to frictionally engage said body portion and slightly compress the same, and the lower portion of said skirt having an inside diameter slightly 20 larger than the inside diameter of the upper portion of the skirt and slightly larger than the outside diameter of said cylindrical body portion.

4. A container comprising a cylindrical body portion of compressible material such as cardboard, and a removable metal cover therefor, said cover having a circular disk top portion, and a skirt depending from the periphery of said disk, a portion of said skirt adjacent said top having an inside diameter slightly less than the normal outside diameter of said cylindrical body portion, so as to frictionally engage said body portion and slightly compress the same, and the lower portion of said skirt having an inside diameter slightly 25 larger than the inside diameter of the upper portion of the skirt, said upper skirt portion extending downwardly less than half the total depth of the skirt.
